WALL RACK FOR JEWELRY

Betty R. Mann, 719 E. Monterey St.,
Pomona, Calif. 91766

Filed Sept. 18, 1968, Ser. No. 13,602

Term of patent 3½ years

Int. Cl. D6—01

U.S. Cl. D33—3

I claim:

The ornamental design for a wall rack for jewelry, as shown.
